UNITED STATES PATENT OFFICE

GEORGE L. VAN DINTER, OF MISHAWAKA, INDIANA, ASSIGNOR TO MISHAWAKA RUBBER AND WOOLEN MANUFACTURING COMPANY, OF MISHAWAKA, INDIANA, A CORPORATION OF INDIANA

DESIGN FOR AN OVERSHOE

Application filed January 24, 1930. Serial No. 34,264. Term of patent 14 years.

To all whom it may concern:

Be it known that I, GEORGE L. VAN DINTER, a citizen of the United States, residing in Mishawaka, county of Saint Joseph, and State of Indiana, have invented a new, original, and ornamental Design for an Overshoe, of which the following is a specification, reference being had to the accompanying drawing, forming a part thereof.

Fig. 1 is a front perspective view of the outside of an overshoe showing my new design.

Fig. 2 is a view of the inner side of the overshoe.

I claim:

The ornamental design for an overshoe as shown.

GEORGE L. VAN DINTER.
